UNITED STATES PATENT OFFICE.

ARVID WESTERBERG AND THURE HÖGLUND, OF STOCKHOLM, SWEDEN, ASSIGNEES TO AKTIEBOLAGET SUPERIOR, OF STOCKHOLM, SWEDEN, A CORPORATION.

SOOT-CLEANING APPARATUS FOR WATER-TUBE AND SIMILAR BOILERS.

Application filed June 21, 1923. Serial No. 646,880.

This invention relates to soot cleaning apparatuses for water tube and similar boilers of the type comprising a rotatable blow pipe disposed at right angles to the longitudinal direction of the water tubes and having a number of nozzles arranged so as to discharge the cleaning steam at an oblique angle to the axis of rotation of the blow pipe and diagonally into the spaces between the 10 said water tubes.

On rotation of an ordinary blow pipe of said type the steam jet issuing from the obliquely directed nozzles describes a circular, outwardly spreading path around the 15 axis of rotation of said pipe, and, if in a certain position of said rotatably mounted blow pipe the steam jet or the main part thereof will really penetrate diagonally into the spaces between the water tubes without 20 striking other tubes than those belonging to the row of tubes most remote from the nozzle, the steam jet will in another angular position of the rotary blow pipe also hit water tubes located at a less distance from 25 the nozzle. The part or parts of the steam jet striking the last mentioned tubes will thus be deflected and interfere with the momentarily active part of the steam jet proceeding directly through the diagonal 30 space between the water tubes, thereby considerably reducing the cleaning effect of the last mentioned part of the steam jet and thus the activity of the whole apparatus.

The main object of the present invention 35 is to avoid the said drawback, i. e. to provide for that a main part of the steam jet will penetrate into the space between the water tubes at any angular position of the blow pipe without being interrupted by the part 40 or parts of the steam jet which are deflected.

With the above and other objects in view, the invention consists essentially in this that the outlet openings of the nozzles have such a form as to impart a fan-shape to the issuing steam jet and such a direction that the plane indicating the main extension of said fan-shaped steam jet forms an angle other than 0° with the axis of rotation of the blow pipe. By such means that part of the steam 50 jet, which strikes a water tube will be deflected into a plane other than that containing the momentarily active part of the steam jet and thus will not interfere with said latter part.

55 The invention consists further of the novel

construction and arrangement of parts as will be hereinafter more particularly described, and then claimed, and in describing the invention in detail, reference will be had to the accompanying drawings illustrating a preferred embodiment thereof.

Fig. 1 is a longitudinal section of a water tube boiler provided with a soot cleaning apparatus according to the invention. Fig. 2 is an axial section through the rotary blow pipes on an enlarged scale. Fig. 3 is a cross-section of a blow pipe on a still enlarged scale showing the special arrangement of the nozzle. Fig. 3^a is an axial section thereof showing also a projection of the end surface 70 of the nozzle. Fig. 3^b is an end view of a somewhat modified nozzle. Fig. 4 is a cross-section along line 4—4 of Fig. 2 on an enlarged scale. Fig. 5 shows details of the piping.

Referring particularly to Figs. 1 and 2, 1 designates the water tubes to be cleaned and 10 a number of blow pipes disposed at right angles to the longitudinal direction of said water tubes. Each of said blow pipes 10 is provided with a number of nozzles 2 having outlets arranged so as to discharge the steam at an oblique angle to the axis of rotation of the blow-pipe and diagonally into the spaces between the water tubes, as apparent from Fig. 2. The blow pipes 10 are rotatably mounted on the water tubes 1 by means of specially devised straps 9 and are rotated by means of sprocket-wheels 12, secured to the outer free ends of the blow 20 pipes, and chains 13 running over said sprocket-wheels, as apparent from Fig. 1.

As shown in Figs. 3 and 3^a, the inlet opening 14 of each nozzle 2 is comparatively small and of a substantially circular cross-section. On the other hand, the outlet opening 15 of the nozzle is elongated so as to impart a fan shape to the steam jet issuing forth. The longitudinal axis of the said outlet opening 15 (line E—E of Fig. 3^a) is 100 inclined to the plane G—G determined by the axis of rotation of the blow pipe 10 and by the centre of the inlet opening 14 of the nozzle, so that the plane indicating the main direction of the fan-shaped steam jet will 105 form an angle with said axis of rotation. It will also be seen from Fig. 3^a that the outlet opening of the steam nozzle is unsymmetrical to the plane G—G and, likewise, unsymmetrical to any other plane determined 110

by the said axis of rotation. As further apparent from Fig. 3 the outlet opening 15 is somewhat wider at the centre than at the ends.

When the main direction of the steam jet 5 is such as to be directed toward the diagonally opposed corner of that compartment of the boiler wherein the apparatus in question is situated, obviously the steam jet will have to travel a longer distance, in order to 10 hit the remotest water tubes, than when the main direction is at right angles to the water tubes. Therefore, it is necessary to make the steam jet somewhat more powerful in the first-mentioned direction than in 15 the latter direction. For this reason, the outlet opening of the steam nozzle is somewhat enlarged in the centre, as mentioned.

Blow pipes, which are situated in such boiler compartments that are long with respect to the cross-wise direction (as is the 20 blow pipe 10 located at the left hand end of Fig. 1), should for analogous reasons be provided with nozzles, the outlet opening of which is larger at the one end than at 25 the other. Such an embodiment is shown in Fig. 3^b, the outlet opening 15 being in this case defined by two circular arcs (at the ends) united by two straight lines.

In Fig. 4, representing a cross section on 30 an enlarged scale along the line 4—4 of Fig. 2, 10 designates the rotary blow pipe having a steam supply opening 17. 11 is a fixed casing, to the lower screw-threaded part 19 of which the steam piping 20, Fig. 35 5, is to be connected. When the rotary pipe 10 is so displaced as to cause the opening 17 to be directed upwardly, the steam supply will be cut off from the movable part. In the same figure the position of a steam nozzle 40 2 is shown by dotted lines.

The said cut-off means permit of an independent operation of each blow pipe per se. Therefore, it is not necessary to install more than one particular steam valve 21, 45 Fig. 5, for the whole plant of a boiler. The last-mentioned figure shows the pipe system for a boiler. 22 is the main steam pipe, and 10 are the blow pipes. 30 is the connecting pipe, and 31 is a drain cock.

50 What we claim as new and desire to secure by Letters Patent of the United States is:—

1. The combination of a water tube boil-

er and a cleaning apparatus therefor, said apparatus comprising a rotary blow pipe 55 disposed substantially at right angles to the longitudinal axis of the boiler tubes and having nozzles for discharging the cleaning fluid diagonally into the adjacent spaces between the water tubes, the outlet 60 opening of each nozzle having such a form as to impart a fan-shape to the steam jet issuing therefrom, and so arranged as to cause the jet to travel in a plane oblique in two directions to the axes of the boiler tubes. 65

2. The combination of a water tube boiler and a cleaning apparatus therefor, said apparatus comprising a rotary blow pipe disposed substantially at right angles to the longitudinal axis of the boiler tubes and having nozzles for discharging the cleaning fluid diagonally into the adjacent spaces between the water tubes, the outlet opening of each nozzle being unsymmetrical with 70 relation to any plane coinciding with the axis of the blow pipe and having such a form as to impart a fan-shape to the steam jet issuing therefrom, and so arranged as to cause the jet to travel in a plane oblique in two directions to the axes of the boiler tubes. 75

3. The combination of a water tube boiler and a cleaning apparatus therefor, said apparatus comprising a rotary blow pipe disposed substantially at right angles to the longitudinal axis of the boiler tubes and having nozzles for discharging the cleaning fluid diagonally into the adjacent spaces between the water tubes, the outlet opening of each nozzle having such a form as to 80 impart a fan-shape to the steam jet issuing therefrom, and so arranged as to cause the jet to travel in a plane oblique in two directions to the axes of the boiler tubes, said blow pipe having a steam supply opening 85 at the proximity of the one end and being seated at the said end in a fixed casing, to which steam is supplied, said casing bearing tightly against part of the circumference of the blow pipe so as to cut off the steam supply to the said opening of the blow pipe, when 90 said pipe occupies certain angular positions. 100

In testimony whereof we affix our signatures.

THURE HÖGLUND.
ARVID WESTERBERG.
